UNITED STATES PATENT OFFICE.

HANS BEHREND, OF SÜDENDE, NEAR BERLIN, GERMANY, ASSIGNOR TO SIEMENS-SCHUCKERT WERKE G. M. B. H., OF BERLIN, GERMANY, A CORPORATION OF GERMANY.

METHOD OF FORMING JUNCTION AND FEEDING POINTS IN ELECTRICAL AERIAL DISTRIBUTION SYSTEMS.

No. 918,262.

Specification of Letters Patent.

Patented April 13, 1909.

Application filed May 21, 1908. Serial No. 434,111.

To all whom it may concern:

Be it known that I, HANS BEHREND, a subject of the German Emperor, and residing at Südende, near Berlin, Germany, have 5 invented an Improved Method of Forming Junction and Feeding Points in Electrical Aerial Distribution Systems, of which the following is a specification.

The subject-matter of the present invention is a new method of forming junction and feeding points at the supporting points or masts of aerial distribution systems.

For explaining the invention some definitions of terms used hereinafter will first 15 be given. By "sections of conductors" is meant a feeder or a conductor forming a part of lighting or power distributing system with a distinct starting and terminating point, but not of any determined length.

20 By a "junction point" is broadly understood the uniting point of a plurality of sections of conductors of like polarity in a certain location of the system, at which these conductors are electrically connected together.

25 Where no electrical connection between two conductors is desired, these conductors cross one another, and the place of intersection of such conductors which are insulated from each other is called an "intersection point", but not a "junction point". The actual electrical connection of 30 different sections of conductors of like polarity will be denoted in the following description as a "junction center", regardless 35 of its extension and position relatively to the sections and to its construction.

The actual number of junction points formed at one place depends upon the number of conductors of different polarity in 40 the distribution system. For example, the continuous current two wire system and the single phase alternating current system each form two, whereas the direct or continuous current, and three phase alternating current, 45 three-wire systems each form three junction points at each place of union. Since masts are generally selected for such places of union for carrying several groups of feeders in aerial systems, these masts are herein- 50 after called briefly "junction point masts".

If the "junction centers" of the junction points are supplied with electrical energy

through mains from the generating station, each "junction point" becomes a feeding point and the "junction point mast" is 55 called a "feeding mast". When the current from the generating station arrives at the "junction center" of a feeding point, it finds as many paths as there are "sections" extending from the feeding point. It is customary 60 to safeguard each of these sections by a safety device, except in case of neutral conductors which are grounded at one or more points. Therefore also at pure junction points the current flows from the junction centers only through safety devices into the outer conductors or sections of the distribution system. Thus if a current flows from any one section across a junction point to another section, it must necessarily pass 65 two safety devices in series, between which the junction center of the two sections is located. If two optional sections form together an angle of 180°, or one approximately as great, such an arrangement shall 70 be hereinafter called a "train of conductors". Such a train of conductors is equivalent 75 with a junction point having only two sections, and always contains two safety devices connected in series, the place of electrical contact of which is identical with the above defined junction center.

In the method of forming junction points heretofore employed, the different sections were arranged substantially radially to the 85 junction point, and the junction center of the system was generally constructed in the form of a ring surrounding the mast concentrically, from which ring the individual sections extended like rays. Such junction 90 points have been made use of in various kinds of constructions and arrangements, but with regard to their manner of electrical connection, they are all represented by like diagrams, as is shown for instance in Figure 1 95 for single pole conductors, and in Fig. 2 for a continuous current three-wire system having a neutral conductor without a safety device. Whether the rings representing the junction center are arranged horizontally 100 side by side, or vertically one above the other, is immaterial. The conductors of like polarity are almost always arranged in the same horizontal plane, and each section is an

independent unit of perfectly equal value relatively to the others.

The methods known heretofore of forming junction points have a number of disadvantages and defects. The rings carrying the insulators have a very great weight and form a heavy load on the junction point mast. In addition, a large number of insulators is necessary, so that this structure is not only expensive, but also complicated and its erection very difficult. Furthermore the insulator supports are liable to be bent, or at least subject to severe strain.

The principal object of the present invention is to provide a method by means of which junction points in aerial distribution systems may be made considerably simpler and cheaper than heretofore.

The invention consists in always joining two of any number of conductors of like polarity at that particular point of the system together to form trains of conductors with two safety devices between them, and in arranging the trains of conductors of like polarity laterally of the mast and in different horizontal planes. The junction point of all the conductors is then formed by connecting the junction centers of the trains.

In order that the invention may be clearly understood reference is made to the accompanying drawings in which various modifications of carrying out this object is represented diagrammatically by way of example, and in which:

Figs. 1 and 2 show arrangements known heretofore and referred to above. Figs. 3 to 5 show trains of conductors arranged laterally of the mast and in different horizontal planes. Figs. 6 to 9 are elevations of some forms of insulators and conductors used in accordance with the present invention, and Fig. 10 is a top plan view of the insulator and conductors shown in Fig. 9.

Referring to the drawings and particularly to Fig. 3, the sections 1_1 and 1_2 and the sections 1_3 and 1_4 represent two trains of conductors which cross one another. In order to produce a junction point, the junction centers a_1 and a_2 of the two trains of conductors are electrically connected together by the conductor f . In Figs. 4 and 5 also the combination of each two conductors into one train of conductors is shown. By connecting the junction center a_1 to a_3 and a_2 to a_4 by means of conductors f , f the junction points of each two trains crossing each other are formed. The trains of conductors of like polarity are always located in different horizontal planes in order to prevent their short circuiting behind the safety devices. It is, however, of no importance whether the trains of conductors of different polarity are arranged horizontally side by side, or vertically one above another.

Preferably conductors will always be chosen to form a train, which form with one another an angle of about 180° , so that the insulator supports will have no tendency to bend laterally whereby an extremely simple arrangement of wires is obtained.

In each train of conductors are two safety devices connected in series, which should be insulated in any suitable manner from the junction point mast. In Figs. 6 to 10 some structural forms are represented by way of example which may be employed according to the present invention. Fig. 6 shows the employment of two insulators i_1 and i_2 of known kind for a train of conductors l_1 , l_2 , from the junction center a of which the current flows through the safety devices s_1 and s_2 into the conductors l_1 and l_2 . In the arrangement according to Fig. 7 the well known suspended safety devices carried by the conductor itself and only one insulator i are employed for the train of conductors l_1 , l_2 . These devices are illustrated in this figure with a protecting shell, and are in character similar to those shown for instance in Fig. 6, in which figure the protecting shell is removed. Each conductor in Fig. 7 serves at the same time for supporting the safety device. The two lines protruding freely from the safety devices s_1 , s_2 in Fig. 7 are meant to represent arc extinguishers which come into action when the fuse melts, and which operate in a similar manner as the well known two horned lightning arresters used in free suspended overhead conductors. Since the particular structure of the safety device has no bearing on this invention, detail illustration and description thereof is omitted. It is preferable however to combine the two safety devices with the insulator so that the two individual sections of conductors may be fastened thereon simultaneously, because thus the consumption of material is reduced and the erection very much facilitated. In Figs. 8 to 10 insulators are represented which are particularly suitable for forming junction and feeding points according to the present invention. The arrangement according to Fig. 8 consists of a casting g carried by the insulator i which casting carries three insulators between which the safety devices s_1 and s_2 are arranged. The sections of conductors l_1 and l_2 are led to corrugated cylindrical insulators r and are connected with each other through the two safety devices by means of the connecting wires k_1 , k_2 . In the arrangement according to Figs. 9 and 10, the wires l_1 and l_2 terminate in loops which are placed in grooves on the insulator i and are electrically insulated thereby. The upper part t of the insulator is formed in such manner that it can hold two fuses or fuse switches s_1 and s_2 , one end of which is connected to the wires l_1 and l_2 by

the flexible conductors k_1 and k_2 respectively, whereas their other ends are electrically connected with each other through the bar a which is provided with terminals and which forms the junction center.

5 An important advantage of the above described arrangements is that many conductors extending from one point may branch off conveniently and in good order with a minimum number of insulators, and that the conductors are protected on all sides by fusible cut-outs. Moreover the erection of the system is considerably simplified by this new arrangement, as all the conductors 10 are disposed so as if only intersection points existed, without the wires being electrically connected, and not as if there were junction and feeding points. The connection of the junction centers of the several 15 insulators with each other or with the mains in the manner herein described represents a standard distribution system having conductors, which are safeguarded on all sides.

I claim:

20 1. Method of forming junction and feeding points of a plurality of sections in electrical aerial distribution systems, consisting in pairing an optional even number of sections of conductors of like polarity into half 25 the number of trains of conductors, each train containing two safety devices in series

with the junction center of said sections between said devices, and in arranging said trains of conductors of like polarity laterally of, and in different planes on a junction mast, and in electrically connecting the junction centers of said trains of like polarity, located between said safety devices.

2. Method of forming junction and feeding points of a plurality of sections in electrical aerial distribution systems, consisting in pairing an optional number of sections of conductors of like polarity into half the 30 number of trains of conductors, each train containing two safety devices in series with the junction center of said sections between said devices and in arranging said trains of conductors of like polarity laterally of their supporting mast said trains being supported by insulators optionally arranged in different 35 planes on said mast and in electrically connecting with each other the junction centers of said trains of like polarity, located between said safety devices.

40 In testimony whereof I have signed my name to this specification in the presence of 45 two witnesses.

HANS BEHREND.
